BUFFER MECHANISM FOR PASSENGER CARS

Vinton E. Sisson, Winnetka, Ill., assignor to Union Metal Products Company, Chicago, Ill., a corporation of Delaware

Application April 15, 1933, Serial No. 666,267

14 Claims. (Cl. 105—14)

The invention relates to railway passenger train cars, and more particularly to a mechanism positioned between the end wall of the car and the upper part of the diaphragm face plate, and an object of the invention is to provide a mechanism which yieldingly retains the upper part of the face plate at a predetermined distance from the end wall of the car and in the longitudinal center of the car when the car is not coupled to another car, but allows the face plate to move toward the end wall of the car when the car is coupled to another car and also to accommodate the movements of the car when running.

My device also yieldingly allows the face plate to assume an oblique position when the car is rounding a curve and/or to move laterally of the car under service conditions. Furthermore, the device allows the face plate to move vertically relative to the end wall of the car to allow for the wearing of the lower face plate supports and/or allows one end of the spring to move vertically relative to the other end of the spring because frequently the lower support at one side of the face plate wears more than the support at the other side of the face plate. Furthermore, the face plates and the buffering mechanism are not always accurately installed on the car. My invention accommodates all of the above mentioned movements of the face plate without binding any of the associated parts and at the same time returns the face plate to a predetermined relative position to the end wall of the car when free to do so.

Another object of the invention is to provide such a buffer mechanism wherein a leaf spring is pivotally attached to the face plate and also pivotally attached to the end wall of the car so that the face plate may move vertically without binding any of the associated parts of the buffer mechanism and wherein preferably also the ends of the spring are pivotally and slidably connected to the wall of the car to allow for the spring movements of the leaf spring.

Another object of the invention is to provide such a pivotal connection without the use of a pin or bolt, which experience shows wears considerably and must be renewed.

In my preferred construction the pivotal means comprises two arcuate or semi-cylindrical bearing surfaces engaging each other, which surfaces, when desired, can be allowed to slide upon each other longitudinally of the spring to form a sliding, pivotal connection.

In the drawings:

Fig. 1 is a plan view of the upper buffer mechanism and associated parts in normal position. Fig. 2 is an elevation of Fig. 1. Fig. 3 is a side view of Fig. 2. Fig. 4 is similar to Fig. 1 with the upper buffer mechanism compressed.

Fig. 5 is similar to Fig. 1 showing the diaphragm face plate in an oblique position.

Fig. 6 is a perspective of the end of a railway car showing the usual relation between the end wall diaphragm, diaphragm face plate and upper buffer mechanism.

Figs. 7, 8, 9 and 10 show the relation between the spring, diaphragm face plate and associated parts of the construction shown in Figs. 1 to 5 inclusive.

Figs. 11, 12, 13, 14 and 15 show the relation of the spring, end wall of the car and associated parts of the construction shown in Figs. 1 to 5 inclusive.

Figs. 16, 17, 18, 19, 20 and 21 show the device provided with a separate wearing shoe.

Figs. 22, 23 and 24 show a modification having a bent bolt as a retainer.

Figs. 25, 26, 27 and 28 show a modification having a U bolt as a retainer.

Figs. 29, 30, 31, 32, 33 and 34 show the spring itself formed to provide a semi-cylindrical bearing.

In the drawings the usual parts of the car are shown, such as end wall 2, diaphragm 3 and diaphragm face plate 4.

The preferred form is shown in Figs. 7 to 15 inclusive wherein the brackets or members 8 are mounted upon the end wall of the car substantially equi-distant on each side of the center line of the car and each bracket or member 8 is provided with a preferably concave semi-cylindrical surface 10 with a stop 12 adjacent the inner end thereof.

The leaf spring 14 (shown as a semi-elliptical leaf spring) is provided with preferably convex semi-cylindrical bearings 16 adjacent each end thereof, which slidably and pivotally engage the respective semi-cylindrical surfaces 18 on the spaced apart brackets or members. These figures show a separate bearing member 18 which may be welded, riveted or otherwise fastened to the spring.

The end of the spring is shown in Fig. 15. The bearing member 18 (or portions of the spring) adjacent the opposite ends of the spring engage the stops 13 on respective brackets or members 8 to limit (or stop) the movements of the ends of the spring toward the center of the car and thus limit the movement of the face plate 4 away from the car.

The stops 12 and the spring 14 are preferably associated and arranged so that it is necessary to slightly compress or spread the spring to assemble it with the brackets, therefore, when the spring is released of pressure the bearing members 18 are pulled into engagement with the opposite stops 13 and the face plate 4 is returned to its normal and central position.

Each of the brackets is provided with a substantially horizontal flange on the upper (20) and lower (22) side, respectively, of the arcuate surface 16 and the spindle or part 24 is positioned, 120

between and secured to these flanges, preferably by the bolt 26 which passes through the spindle and apertures in the flanges. This part or spindle is wider adjacent its middle (28) than at its ends 5 and the wider middle is adjacent the horizontal center of the spring so that it retains the bearing 16 on the end of the spring in close proximity to the cylindrical surface 10 on the member or bracket 8 when the pressure is released on the 10 spring; that is, when the car is not coupled to another car. This part 24 is formed so as not to interfere with the rotation of the spring in either direction about its longitudinal axis, as shown in Fig. 3.

15 This part or spindle 24 is preferably symmetrical so that it cannot be improperly applied and so it is immaterial if it rotates about its own axis. The bolt 26 holds the several component parts in operative relation so that to disassemble the device it is simply necessary to remove this bolt. A hole 30 is provided in the stop 12 for the escape of foreign matter. Fig. 14 is a perspective view 20 of the bracket 8.

25 The middle portion of the leaf spring 14 is attached to the diaphragm face plate 4 by the bracket or member 36 which is provided with a semi-cylindrical surface 38 and a semi-cylindrical bearing is provided adjacent a middle of the spring which pivotally engages the cylindrical surface of the bracket. The bracket 36 is provided with a wall or stop 40 adjacent each end of the cylindrical surface which limits (or stops) the longitudinal movement of the spring. The spindle or part 42 is positioned between horizontal 30 flanges 44-46 on the bracket or member 36 and secured thereto by the bolt 48 and have the same relation and perform the same functions as the spindle 24. A hole 50 is provided in each wall 40 for the escape of foreign matter. Fig. 10 is a perspective of the bracket 36.

40 Figs. 16 to 21 inclusive show another modification wherein a separate shoe 74 is provided at each end of the spring, which shoe has a semi-cylindrical bearing 75 engaging the semi-cylindrical surface 76 of the bracket 77. The shoe is provided with a spindle 78 and a wall 79 and a lateral flange 80 on the spring is hooked therebetween and the associated parts are held in an operative 45 relation by the bolt 81 and spindle 82. The flanges of the shoe are tapered at 84 to allow the spring to rotate about its longitudinal axis, as shown in Fig. 21. Figs. 17 and 20 are perspective views of the shoe 74 and bracket 77 respectively.

45 Figs. 22, 23 and 24 show a modified construction wherein a bent bolt 56 passes through apertures in the flanges 58-60 of the bracket 62 with the elbow 64 thereof positioned adjacent the horizontal center of the spring 66 to retain the bearing 68 in close proximity to the cylindrical surface 70 of the bracket 62 when the tension is released from the spring. The lip 72 is provided on one of the flanges to engage the head of the bolt 56 to provide means to prevent the bolt from rotating about its longitudinal axis. The flanges 60 preferably converge as shown to provide bearing surfaces for the head and nut of the bolt. In this modification the bearing 68 on the end of the spring is semi-spherical.

50 Figs. 26, 27 and 28 inclusive show a modification wherein a projection 92 on the bracket 93 is provided with an exterior convex semi-cylindrical surface 94 and the ends of the spring are each formed into an integral semi-cylindrical bearing 95 rotatively and slidably engaging the arcuate surface 94 of one of the brackets. The

end of the spring is formed with a lateral lip 96 which engages the end of the projection (or abutment 92) forming the semi-cylindrical surface to provide the stops heretofore described. The lip 96 and bearing 95 are preferably formed integrally to mutually reinforce each other, as shown in Fig. 28. The curved bolt 97 is preferably concentric with the arcuate surface of the bracket and bearing on the spring. The bracket has a flange 98 provided with a slot 99 for the bolt head and a lower flange 100 provided with an aperture 101 through which the bolt projects and is retained in position by the nut 102. Preferably a carriage bolt with a partially squared shank is used to keep the bolt out of contact with the spring. The bolt may be provided with the shoulder 103 to prevent the bolt from being pulled against the spring. Fig. 27 is a section on line 27-27 of Fig. 26.

55 Figs. 29, 30 and 31 show the end of the spring formed into an integral semi-cylindrical bearing 88, and Figs. 32, 33 and 34 show a construction wherein the end of the spring is rebent over itself and the rebent portion 90 and the end of the spring 91 formed into a semi-cylindrical bearing 100. Fig. 30 is a section on line 30-30 of Fig. 29 and Fig. 33 is a section on line 33-33 of Fig. 34.

60 The arcuate surfaces associated with the end wall or face plate may be either convex or concave and the cooperating bearings on the middle or ends of the spring may be correspondingly concave or convex and still come within the scope of the invention.

65 In the preferred construction, as illustrated, the medial portion of the spring is attached to 110 the face plate and the ends of the spring slide upon the end wall. However, this may be reversed, that is, the medial portion of the spring may be attached to the end wall and the ends of the spring slide upon the face plate, and still come 115 within the scope of the invention.

70 The accompanying drawings illustrated the preferred form of the invention, though it is to be understood that the invention is not limited to the exact details of construction shown and described, as it is obvious that various modifications thereof, within the scope of the claims, will occur to persons skilled in the art.

I claim:

75 1. In a railway car having a wall element and a diaphragm face plate element, a buffer mechanism positioned between said elements comprising a leaf spring, means to pivotally attach the medial portion of the spring to one of said elements, and means to pivotally attach the end portions of the spring to the other of said elements, the axes of said means being substantially parallel to the face of the wall, whereby the elements may move vertically relative to each other.

80 2. In a railway car having a wall element and a diaphragm face plate element, a buffer mechanism positioned between said elements comprising a leaf spring with means to pivotally attach the medial portion of the spring to one of said elements, and means to pivotally and slidably attach the end portions of the spring to the other of said elements, the axes of said means being substantially parallel to the face of the wall, whereby the elements may move vertically and horizontally relative to each other.

85 3. In a railway car having a wall element and a diaphragm face plate element, a buffer mechanism positioned between said elements comprising a member attached to one of said elements

- provided with a semi-cylindrical surface, a leaf spring provided with a semi-cylindrical bearing pivotally engaging said surface, and a part attached to said member with only the middle 5 thereof adjacent the horizontal center of said spring providing means to retain the bearing in close proximity to the said surface when there is no pressure on the spring. 80
4. In a railway car having a wall element and 10 a diaphragm face plate element, a buffer mechanism positioned between said elements comprising a member attached to one of said elements provided with a semi-cylindrical surface, a leaf spring provided with a semi-cylindrical bearing 15 pivotally engaging said surface, said member having a horizontal flange on each side of said surface, a bent bolt passing through apertures in said flanges with the elbow thereof adjacent the horizontal center of said spring providing 20 means to retain the bearing in close proximity to the said surface when there is no pressure on the spring, and means to prevent the bolt from rotating about its longitudinal axis. 90
5. In a railway car having a wall element and 25 a diaphragm face plate element, a buffer mechanism positioned between said elements comprising a member attached to one of said elements provided with a semi-cylindrical surface with a wall at each end thereof, and a leaf spring provided 30 with a semi-cylindrical bearing pivotally engaging said surface between said walls so as to limit the longitudinal movement of the spring. 100
6. In a railway car having a wall element and 35 a diaphragm face plate element, a buffer mechanism positioned between said elements comprising a member attached to one of said elements provided with a semi-cylindrical surface, and a leaf spring provided with a semi-spherical bearing pivotally engaging said surface the axis of 40 said semi-cylindrical surface being substantially parallel to said end wall. 105
7. In a railway car having a wall element and 45 a diaphragm face plate element, a buffer mechanism positioned between said elements comprising spaced apart members on one of said elements, each member having a semi-cylindrical surface, a part on the other of said elements provided with a semi-cylindrical surface, and a leaf spring provided with a semi-cylindrical bearing adjacent each end thereof and slidably engaging the said surfaces on the members, said spring also provided 50 with a semi-cylindrical bearing adjacent its medial portion pivotally engaging the said surface on said part. 110
8. In a railway car having a wall element and 55 a diaphragm face plate element, a buffer mechanism positioned between said elements comprising spaced apart members on one of said elements, each member having a semi-cylindrical surface, a part on the other of said elements provided with a semi-cylindrical surface, a leaf spring provided with a semi-cylindrical bearing adjacent each end thereof pivotally and slidably engaging the said surfaces on the members, said spring also provided 60 with a semi-cylindrical bearing adjacent its medial portion pivotally engaging the said surface on said part. 115
9. In a railway car having a wall element and 65 a diaphragm face plate element, a buffer mechanism positioned between said elements comprising spaced apart members on one of said elements, each member having a semi-cylindrical surface, a part on the other of said elements provided with a semi-cylindrical surface, a leaf spring provided with a semi-cylindrical bearing adjacent each end thereof pivotally and slidably engaging the said surfaces on the members, said spring also provided with a semi-cylindrical bearing adjacent its medial portion pivotally engaging the said surface on said part, and means to limit the movement of the medial portion of the 70 spring relative to the element to which it is attached. 120
10. In a railway car having a wall element and 75 a diaphragm face plate element, a buffer mechanism positioned between said elements comprising spaced apart members on one of said elements, each member having a semi-cylindrical surface with a stop adjacent the inner end thereof, a part on the other of said elements provided with a semi-cylindrical surface with a wall adjacent each end thereof, and a leaf spring provided with a semi-cylindrical bearing adjacent each end thereof pivotally and slidably engaging the said surfaces on the members, said spring also provided with a semi-cylindrical bearing adjacent its medial portion pivotally engaging the said surface on said part between said walls so as to limit the longitudinal movement of the spring, said stops on the members associated and arranged with the spring to limit the sliding movements of the ends of the spring toward the center of the car whereby the movement of the face plate away from the car is limited. 125
11. In a railway car having a wall element and 80 a diaphragm face plate element, a buffer mechanism positioned between said elements comprising a bracket provided with a projection having a semi-cylindrical exterior surface, said projection having an abutment at one end thereof, and a leaf spring with one end formed into an integral semi-cylindrical bearing rotatably and slidably engaging said surface, the outer end of said spring formed with a laterally extending lip engageable with said abutment to limit the sliding movement of the spring upon the said projection. 130
12. In a railway car having a wall and a diaphragm face plate, a buffer mechanism between said wall and face plate comprising a leaf spring, means to pivotally attach the medial portion of said spring to the face plate, and means to pivotally and slidably attach the end portions of the spring to the wall, the axes of said means being substantially parallel to the face of the wall, whereby the elements may move vertically and horizontally relative to each other. 135
13. In a railway car having a wall element and 85 a diaphragm face plate element, a buffer mechanism positioned between said elements comprising a leaf spring, means to pivotally attach the medial portion of the spring to one of said elements, and means to pivotally attach the end portions of the spring to the other of said elements, the axes of said means being substantially parallel whereby the elements may move vertically relative to each other. 140
14. In a railway car having a wall and a diaphragm face plate, a buffer mechanism between said wall and face plate comprising a leaf spring, means to pivotally attach the medial portion of said spring to the face plate, and means to pivotally and slidably attach the end portions of the spring to the wall, the axes of said means being substantially parallel whereby the elements may move vertically and horizontally relative to each other. 145

VINTON E. SISSON.
